UNITED STATES PATENT OFFICE.

SANARA GENNETTE, OF HANCOCK, MICHIGAN.

STORE FIXTURE.

Application filed April 18, 1922. Serial No. 554,677.

To all whom it may concern:

Be it known that I, SANARA GENNETTE, a citizen of the United States, residing at Hancock, in the county of Houghton and 5 State of Michigan, have invented certain new and useful Improvements in Store Fixtures, of which the following is a specification.

This invention relates to improvements in 10 store fixtures, and has for one of its objects to provide a device of this character comprising a plurality of conveniently arranged receptacles and compartments accessible from all sides.

15 Another object of the invention is to provide a device of this character including a supporting casing, a plurality of inclined open receptacles, a closure for each receptacle, and runways in the casing in which the 20 closures operate when in withdrawn position.

With these and other objects in view the invention consists in certain novel features of construction as hereinafter shown and 25 described and then specifically pointed out in the claims, and in the drawing illustrative of the preferred embodiment of the invention:—

Figure 1 is a perspective view of the improved device.

Fig. 2 is a section on the line 2—2 of Fig. 3.

Fig. 3 is a perspective view illustrating a modification in the construction.

35 Fig. 4 is a section on the line 4—4 of Fig. 3.

The improved device includes a base member 10 upon which a floor member 11 is supported in spaced relation by outward inclined rails 12.

The floor member 11 thus overhangs the edges of the base member 10, as shown.

The ends of the supporting casing are represented at 13, and may be paneled as shown 45 at 14 in Fig. 3, with a mirror in the panel. Bearing upon the ends 13 is a casing or body including a solid bottom 15, ends 16, relatively low sides 17, a longitudinally directed intermediate partition 18, and a plurality 50 of transverse partitions 19 in spaced relation.

Bearing upon the partitions 18 and 19 is a flat member 20 of less width than the member 15 with the upper edges of the end members 16 and the transverse partitions 19 sloping downwardly and outwardly between the

outer edges of the member 20 and the upper edges of the member 17.

By this means a plurality of pockets or receptacles are formed along each side of 60 the device, each of the pockets having a hinged closure 21, preferably with a glass panel as indicated.

Bearing upon the member 20 are upper casings including bottom 22, spaced sides 65 23, ends 24, top 25 and transverse partitions 26, the sides 23 being glass paneled so that the contents of the compartments of the casings are visible.

By this arrangement a receptacle is 70 formed comprising an upper portion above the partition or bottom 22 and a lower portion below the partition, the lower portion extending in advance of the upper portion and separated therefrom by the longitudinal 75 guideway defined by the members 20 and 22.

By this arrangement if the lower casing portion is to be temporarily opened, the closure 21 is merely folded upwardly against the front of the upper receptacle portion as 80 shown in Figs. 2, 3 and 4, and without displacing the guide member 38, but thereby obstructing the transparent front of the upper portion, but if the lower receptacle portion is to be permanently covered or un- 85 covered without obstructing the front of the upper portion, the guide member 38 is moved into the guideway between the members 20 and 22 carrying the closure 21 with it. It is of great advantage to be able to 90 quickly uncover the lower receptacle portion when a sale is to be made, which may be done by simply turning the closure up against the upper receptacle portion and temporarily obstructing the latter but it is 95 of equal advantage to be able to uncover the lower receptacle portion without obstructing the upper receptacle portion. Either arrangement is possible with the simple construction disclosed by applicant. 100

A space is left between the member 20 and the bottom 22 of the narrower upper casing to form a runway and hingedly attached at 37 to the upper and inner edge of each closure 21 is a guide member 38 slideable in the guideway, so that the closures 21 may be moved bodily back into the body of the device, or folded up against the body, as may be preferred.

In the structure disclosed in Figs. 1 and 110 2 the smaller upper casings are shown in spaced relation with a portion of the top

20 of the lower casing unobstructed to form a counter, over which goods may be sold, and the top members 25 each formed with an opening 27 and a hinged closure 28 for 5 each of the compartments formed by the partitions 26 and ends 24. By this means the compartments of the upper casing are independently accessible and the contents visible through the glass side panels.

10 Built into the space between the floor portions 11 and the bottom 15 of the lower casing are a plurality of receptacles 29 in inclined position with their upper ends open and normally accessible externally of the 15 shorter sides 17 of the lower casing.

Extending between the ends 13 of the body of the device and spaced below the lower face of the member 15 are supports 30 which produce runways for closure members 31 for the inclined receptacles 29. The closures 31 are slidable in the runways to render the receptacles 29 accessible as illustrated at the right in Fig. 2, or to cover the receptacle as indicated at the left in Fig. 2.

25 Each closure 31 is provided with means for preventing them being displaced when moved into outer position, for instance by stops 32, as shown in Fig. 2.

The closures 31 are preferably of glass 30 panels rendering the contents of the compartments visible.

A shelf 33 may be attached to one or both of the ends 13.

At one side the receptacles 29 are each 35 formed with an inclined floor 39, while each compartment at the other side is defined by a vertical rear partition 40, to provide compartments of greater size.

In Figs. 3 and 4 some modifications in the 40 construction are shown. In the modified structure the upper casing is formed with hinged closures 34, and receptacles 35 similar to the receptacles 29, are hingedly con-

nected at their lower outer edges to the floor 11 and movable into outer position as shown 45 at 36, to provide access to the contents of the receptacle, or movable in the body when not in use as at the right in Fig. 4.

The improved device is designed for use in wholesale or retail stores for the display 50 of various articles for sale or inspection and wherein goods are rendered visible from all sides and independently accessible.

The improved device may be constructed 55 of any required size and contain any desired number of the various compartments and of any suitable material.

The preferred embodiment of the invention is disclosed in the drawings and set forth in the specification, but it will be understood that modifications within the scope 60 of the claimed invention may be made in the construction without departing from the principle of the invention or sacrificing any of its advantages.

Having thus described the invention what 65 is claimed as new is:—

A device of the class described comprising a receptacle including an upper portion having a transparent front and a lower portion 70 opening upwardly and extending in advance of the upper portion and a guideway between the receptacle portions, a guide member movable in the guideway, and a closure for the forwardly extending portion of the 75 receptacle hingedly united to the guide member and movable with the closure into the guideway, whereby the lower receptacle portion may be uncovered and the closure thereof disposed between the receptacle portions 80 without obstructing the upper receptacle portion.

In testimony whereof, I affix my signature hereto.

SANARA GENNETTE.
